H. D. HINELINE ET AL

THERMAL RELAY

Filed March 5, 1923

Fig. 1.

UNITED STATES PATENT OFFICE.

HARRIS D. HINELINE, OF PITTSBURGH, AND WALTER G. MYLIUS, OF WILKINSBURG, PENNSYLVANIA, ASSIGNORS TO WESTINGHOUSE ELECTRIC AND MANUFACTURING COMPANY, A CORPORATION OF PENNSYLVANIA.

THERMAL RELAY.

Application filed March 5, 1923. Serial No. 622,795.

Our invention relates to electrical protective devices and more particularly to thermal relays.

One object of our invention is to provide a thermal relay that shall have sufficient time interval in the operation thereof to effect protection of electrical apparatus from overloads.

Another object of our invention is to provide a relay of the above-indicated character that shall employ a bimetallic element of such shape that a relatively great degree of heat and, consequently, a relatively large torque, may be developed therein.

Another object of our invention is to provide a relay, of the above-indicated character, that shall be simple and economical in construction and reliable in operation.

Heretofore, considerable difficulty has been encountered in developing sufficient heat in a small bimetallic element because the resistance of the element was too small to obtain torque of the required value.

In view of the difficulty of developing sufficient heat in a bimetallic element of the usual type heretofore used, we provide an element that corresponds in overall dimensions to those previously employed, but which is so slotted as to develop a current-conducting path greatly exceeding in length the former current-conducting paths.

By reason of the shape of the bimetallic element, the length of the current-conducting path in each strip is greatly increased in proportion to the lineal length of the strip, and by the disposition of the several strips in either series or parallel connection a considerable electrical-conducting path is confined in a minimum cubical area, thereby greatly multiplying the effective resistance of the bimetallic element. The total heat and, consequently, the torque developed, are correspondingly increased.

Figure 1 is a longitudinal sectional view of a thermal relay embodying our invention.

Fig. 2 is a similar view taken at right angles thereto.

Fig. 3 is a cross-sectional view of the thermal relay taken along the line III—III of Fig. 1.

Fig. 4 is a detail thereof.

Fig. 5 is a diagrammatic illustration of electrical circuits and apparatus embodying our invention.

In the preferred form of our invention, a cylindrical member 1 of non-conducting material has its opposite ends closed by metallic caps 2 and 3 comprising metallic ferrules 4 and 5 respectively. Binding posts 6 and 7, in the form of clamping screws, extend through the caps 2 and 3, respectively, and also serve as securing means for brackets 8 and 9, respectively. 55

Bracket 9 comprises a main body portion 11 extending longitudinally of the cylinder 1, an end portion 12 at a right angle thereto engaging binding post 7, and an end portion 13 at a slight angle to the main body portion 11. Secured to the body portion 70 11 is an electrical conductor 14 which extends through cap member 3, but is insulated therefrom as is shown in Fig. 1. Conductor 14 is provided with a binding post 15. As is shown in Fig. 4, members 11 and 14 are 75 secured together by rivets 16 and insulating material in such manner that no electrical connection exists between them.

Secured to the end portion 13 of bracket 9 and to the bracket 8 by means of rivets 80 17, is a bimetallic element 18. The details of this connection are shown in Fig. 3, wherein a plurality of bimetallic strips 21 to 26 are shown held in mechanical connection to one another and to members 8 and 9, 85 by the rivets 17. Between each pair of bimetallic strips there is placed a layer of insulating material, and similar insulating material is placed between certain portions of brackets 8 and 9 and the adjacent bimetallic strips 21 and 26, respectively, as is shown in Fig. 3.

The free end of the bimetallic element 18 is slightly offset, as at 27, into parallel relation with body portion 11 of the bracket 9. 95 A contact member 28 is mounted on the face of bimetallic member 18 adjacent to the portion 11, but not in electrical contact therewith and is soldered, over one half of its surface, to the member 18, the other half of its surface being insulated therefrom. A contact member 29 is adjustably secured to the conductor 14 and passes through an enlarged opening 31 in the body 100

portion 11 without contact therewith. An opening 32 is provided in the cylinder 1 for adjustment of the contact member 29.

In operation, we place our relay in suitable clips (not shown) in the electrical circuit to be protected. Electrical contact is made between these clips and the ferrules 4 and 5. Considering the ferrule 4 to be the positive terminal, electrical current traverses a portion of the cap member 2, binding post 6, bracket 8 and the bimetallic strip 21 soldered to the bracket 8, as is shown at the right hand side of Fig. 3.

It is to be noted that the middle and left-hand sections of the strip 21 are insulated from the bracket member 8. Current then traverses the several loops of the bimetallic strip, shown in Fig. 2, reaching the end of the strip 21, as shown at the left-hand side of Fig. 3, where soldered connection is made with the next bimetallic strip 22. It is to be observed that strips 21 and 22 are insulated from one another at all other points on their surfaces. Current then traverses the strip 22 in a direction opposite to that taken in traversing the strip 21, and at length reaches the end shown at the right of Fig. 3, where a soldered connection is made to the strip 23. This alternating connection between the bimetallic strips is repeated until the current reaches bimetallic strip 26 which has a soldered connection to member 9, shown at the right of Fig. 3. Strip 26 is insulated from the member 9 at its middle and left-hand sections.

Current then traverses portion 13 and 11 of bracket 9, the binding post 7, the cap 3, and ferrule 5. It will be seen that normally no current traverses the member 14 and that appreciable space exists between members 11 and 18 by reason of the slight offset of the end 13.

It is obvious that a parallel electrical connection may be had through the bimetallic member 18 by omitting the insulation between the several strips, or by soldering the several ends of these strips on both sides of Fig. 3, rather than in the stagger relationship shown.

Upon the occurrence of an excessive current in the bimetallic strip 18, a large amount of heat will be liberated. This heat will cause the member 18 to be deflected or buckled in a predetermined direction. Contact member 29 is adjusted to engage contact member 28 upon a predetermined amount of deflection of the bimetallic element 18. Upon the closing of these contact members, electrical contact is made between the strip 26 of the bimetallic element and conductor 14.

In Fig. 5, we have shown a motor M receiving current through a circuit 33, comprising our thermal relay R and a circuit interrupter 34, from a source of electro-motive force G. We prefer to connect our

relay in series with the device to be protected, although it may be connected in shunt circuit with such device when desired. Upon the closing of contact members 28 and 29, as heretofore described, an electrical circuit 35, connected to the binding post 15, is energized. This circuit controls a tripping mechanism 36 for the circuit interrupter 34, which is accordingly brought to the open circuit position, thereby interrupting the electrical circuit comprising the device M.

It is thus seen that we have devised a thermal relay which is simple to construct, which has minimum number of parts, and which is rugged and adapted for hard usage.

Although we have shown one form of relay embodying a slotted bimetallic element, we do not limit the element to the particular mode of slotting that is illustrated, or to a relay embodying an element having the particular arrangement that is illustrated, as various modifications may be made therein within the spirit and scope of the invention as set forth in the appended claims.

We claim as our invention:

1. In a thermal relay, a thermo-responsive element comprising a plurality of bimetallic strips, said strips having electric-insulating material inserted between each pair of adjacent bimetallic strips, means for electrically connecting each bimetallic strip to the adjacent bimetallic strips at opposite edges thereof, and a single electrical connection to each of the outer bimetallic strips.

2. In a thermal relay, a thermo-responsive element comprising a plurality of strips of bimetal, each of said bimetallic strips having at least an electrical length of substantially twice its linear length, electric-insulating material inserted between each pair of adjacent bimetallic strips, each bimetallic strip being electrically connected to the adjacent bimetallic strips, a single connection being so made at each end of said bimetallic strips that electrical connection through the bimetallic strips of said thermo-responsive element is secured.

3. In a thermal relay, a cylindrical body member, end members for said cylindrical member comprising metallic ferrules, a rigid mechanical means comprising a portion of a bimetallic element connecting said ferrules, said mechanical connecting element comprising a normal electrical connection between said end members.

4. In a thermal relay, a cylindrical body member, end members for said cylindrical member comprising metallic ferrules, a rigid mechanical means comprising a portion of a bimetallic element connecting said ferrules, said mechanical connecting means comprising a normal electrical connection between said end members, and a conductor extend-

ing through one of said end members mechanically carried by said mechanical connecting means, and means for closing an electrical circuit between said conductor and 5 said bimetallic element under predetermined conditions.

5. In a cartridge-type thermal relay, a body portion, a metallic member secured to one end of said body portion, a bimetallic 10 element connected to said metallic member, a second metallic member mechanically secured to, and electrically insulated from, said metallic member and passing through an opening in said end portion and means 15 for completing an electrical circuit between said bimetallic element and the second metallic member under predetermined conditions.

6. In a cartridge type thermal relay, a 20 body portion, a metallic member secured to one end of said body portion, a bimetallic element connected to said metallic member, a second metallic member mechanically secured to and electrically insulated from said 25 metallic member and passing through an opening in said end portion and means comprising a contact member mounted on said second metallic member and extending through an opening in the first named metallic member, for completing an electrical circuit between said bimetallic element and the second metallic member under predetermined conditions in this bimetallic member.

7. In a thermal relay of the cartridge

type, a body member, metallic end pieces 35 therefor, a mechanical and electrical connection between said end pieces comprising a metallic bracket secured to one end piece and extending adjacent the other end piece, a second bracket member mounted on the 40 other end piece at one side of the end of the first named bracket, a bimetallic element disposed between said brackets, and means for securing said brackets and said bimetallic element together. 45

8. In a thermal relay of the cartridge type, a body member, metallic end pieces therefor, a mechanical and electrical connection between said end pieces comprising a metallic bracket secured to one end piece 50 and extending adjacent to the other end piece and terminating in a bent portion, a second bracket member mounted on the other end piece at one side of the end of the first named bracket, a bimetallic element so disposed between said brackets and extending in substantially the plane of said bent portion that a space exists between the free end 55 of said bimetallic element and the major portion of the first named bracket, and means for securing said brackets and said bimetallic element together. 60

In testimony whereof, we have hereunto subscribed our names this 24th day of February, 1923.

HARRIS D. HINELINE.
WALTER G. MYLIUS.
